UNITED STATES PATENT OFFICE.

ROBERT B. FINN, OF SAN FRANCISCO, CALIFORNIA.

RETORT-CLEANER.

1,370,201.

Specification of Letters Patent.

Patented Mar. 1, 1921.

Application filed March 10, 1920. Serial No. 364,818.

To all whom it may concern:

Be it known that I, ROBERT B. FINN, a citizen of the United States, and a resident of the city and county of San Francisco, 5 State of California, have invented new and useful Improvements in Retort-Cleaners, of which the following is a specification.

My invention has for its object the provision of means within a condensing chamber, whereby the mouth of a retort opening into said chamber may be readily cleaned of any obstructions, such as condensed material and which would otherwise impede the progress of the fumes into the condensing chamber; and devices whereby the 10 said cleaner may be operated from the outside of the chamber.

My invention is particularly applicable to apparatus for the condensation of metallic 20 fumes, such as the production of zinc dust, and reference is herein made to my copending application, Serial No. 317,603, filed Aug. 14, 1919, wherein are set forth a process and apparatus for the production of zinc 25 dust, to which this my present invention is applicable.

During condensation of metallic fumes in the chamber more or less condensation also takes place within the mouth or neck of 30 the retort, which of necessity is removed from the zone of greatest heat where the metal is volatilized; and this condensation results in an obstruction forming in the mouth of the retort whereby the egress of 35 the metallic fumes is impeded and which thereby retards the rate of production of the zinc dust.

The condensation of metallic fumes must take place in the presence of an inert gas 40 such as nitrogen for the reason that the presence of such a gas as oxygen results in the formation of metallic oxids, which are then found as impurities in the product. It is therefore advisable to keep the condensing chamber and retort sealed from the atmosphere during the progress of the condensation and this implies the sealing of the mouth of the retort to the chamber and the exclusion of any atmospheric contamination.

50 In my invention I provide means whereby the cleaning member, which may be used to remove the obstructions in the mouth of the retort, is actuated from the outside of the condensing chamber and through suit-

able packing so that although the cleaner 55 may be freely operated it is not necessary to open the chamber or to otherwise allow any ingress of air.

By referring to the accompanying drawings my invention will be made clear. 60

Figure 1 is a side elevation, partly in section, of the condensing chamber and retort in assembled position and showing the corresponding normal position of the cleaner.

Fig. 2 shows the same parts as Fig. 1, 65 but at right angles thereto.

Fig. 3 shows a variation in the cleaner and its method of adjustment.

Throughout the figures similar numerals refer to identical parts. 70

The condenser chamber is indicated by the numeral 1, and the retort within which the volatilization occurs is shown at 2. The retort is provided with a neck 3, extended into or connected with the chamber. 75

A furnace within which the retort is heated is shown at 4, and an outlet for the condensates is indicated by the numeral 5. The chamber is preferably mounted upon rollers 6, 7, so that it may be laterally displaced with regard to the retort for recharging the latter. This is accomplished by moving the chamber on the rollers across the floor 8. The chamber is sealed to the retort by any suitable means as by the luting 9 so 80 that the condensation of the fumes from 2 and within chamber 1 takes place without any atmospheric contamination. 85

During the volatilization of the contents of the retort at 2, and the passing of the 90 fumes through the neck 3 more or less condensation takes place so that the neck 3 becomes impeded or congested by condensed material. In the process here described this consists of zinc dust of greater or less fineness depending upon the conditions of circulation, temperature, etc., and to facilitate the action this obstruction must from time to time be removed.

Referring particularly to Figs. 1 and 2, 100 I provide a member 10 which is adapted to move into the mouth, or neck, of the retort, thereby clearing the neck 3 of the said dust or other obstruction and forcing it back into the retort so that it is again volatilized. 105 The member 10 is mounted on the arm 11 which latter swings with the axis 12. The axis 12 is carried in an internally disposed

support 13 and passes through the wall of the chamber 1, where it is supported as at 14, and is also suitably packed by the gland 15 to prevent air contamination with the interior of the chamber.

The arm 11 is fixed to the shaft 12 as by the pin 16 and the shaft may be rotated as by the crank 17 to clear the neck 3. In order to provide for variations in the relative positions of the retort neck 3 to the chamber and cleaning mechanism, as during periods of different treatments, I prefer to provide an adjustment as by the screw threads and nuts at 18 whereby the cleaner head 10 may be relatively varied with respect to the shaft 12, so as to accommodate it to any varied position of the neck 3 or the retort. And I also provide lateral adjustment for the cleaner head 10 and shaft 12, 20 as by collars at 19, 20.

At Fig. 3 I have shown a variation in the construction of the cleaner wherein 21 indicates a rotatable fork or disk ended member, adapted to pass into the mouth or neck 3 and by its rotation and advance into the neck clear the obstruction forcing it back into the retort 2. The fork or disk end 21 is carried upon the arm 22, which in turn is supported from the chamber wall at 23 and provided with a suitable packing gland as 24, the device being operable by hand from the end 25.

The operation is as follows:

The retort 2 is charged and brought to substantially a volatilization heat for the contents, and the chamber 1 is then rolled across the floor 8 on the rollers 6, 7 until the retort mouth 3 engages through a suitable opening with the interior of the chamber 1. The retort and chamber are now luted at 9, or otherwise secured, or sealed together. The fumes from the retort 2 will commence to fill the chamber 1. The air contained in the chamber 1 will now supply oxygen to oxidize the said fumes until such time as the oxygen contained is consumed. The fume oxid, in the present case the oxid of zinc, will now be deposited upon the sloping bottom of the chamber 1, and may be withdrawn from the outlet 5. During this step in the process the gaseous content of chamber 1 has changed from air to inert nitrogen and the metallic fumes issuing through the neck 3 will now continue to

condense in the chamber 1 without oxid 55 contamination.

From time to time condensation in the mouth of the retort 3 will have built up an obstruction to the issuing fumes and the cleaner is now to be operated either by the crank 17, if of the form shown in Figs. 1 and 2, or by the hand member 25 in the type shown in Fig. 3, the head of the cleaner entering the neck 3 and thereby removing the said obstruction by forcing it back into the retort 2 when the fumes will continue to issue from the retort unimpeded and thus maintain the maximum rate of condensation at all times throughout the volatilization of the complete charge of the retort.

I claim:

1. In combination with a retort and condenser chamber, a cleaner mounted within said chamber and movable to clear the mouth of the retort, and operable means external to the chamber and passing thereinto and adapted to operate the cleaner, and devices sealing said chamber around said operable means and from the atmosphere.

2. In a combined retort and condenser, a cleaner for the mouth of the retort located within the chamber, an arm to actuate said cleaner and passing through the chamber wall and packing means around said arm sealing said chamber from the atmosphere.

3. In a combined retort and condenser, a cleaner for the mouth of the retort located within the chamber, an arm to actuate said cleaner and passing through the chamber wall and packing means around said arm sealing said chamber from the atmosphere, and forming a guide for said arm and cleaner movement.

4. The combination of a retort, a condensing chamber within which said retort is adapted to discharge fumes, and a cleaner mounted to move within said chamber and toward and within the mouth of said retort, support means for said cleaner and means external to said chamber constructed and adapted to operate said cleaner, and a device fixed to the chamber wall and through which the means pass sealing the chamber from the atmosphere, as and for the purpose set forth.

In testimony whereof, I have hereunto set my hand at San Francisco, California.

ROBERT B. FINN.
